UNITED STATES PATENT OFFICE

EVA M. REESE, OF CANTON, OHIO

PACK CARRYING HARNESS

Application filed November 7, 1930. Serial No. 493,977.

The invention relates to pack carrying harness, and more particularly to a harness adapted to be worn by newsboys and the like for supporting at the back of the wearer a pack or bag containing a heavy load of newspapers or magazines to be peddled or distributed.

The usual method of carrying a load of papers or magazines is to support a bag at the side of the wearer by means of a single strap leading from the top of the bag diagonally upward across the body and over the opposite shoulder. When this form of bag and strap is used, the entire load is suspended from one shoulder, and continued use tends to cause the wearer to hold that shoulder lower than the other at all times. Moreover, since the weight is suspended directly from the shoulder, the wearer experiences a tendency to lean somewhat forwardly, that is, to become "round shouldered".

The tendency toward "round shoulderness" becomes more accentuated when in carrying a heavy load with the single diagonal strap, the wearer naturally shifts the bag to the rear of his body and leans forward to support some of the weight upon his back.

Various contrivances have been made for carrying such a bag or pack upon the back, and supporting it from both shoulders, but these devices all tend to cause a leaning forward of the shoulders, and consequently an erect posture is not assumed by the wearer.

The persons nearly always employed to peddle and distribute papers or magazines are immature boys who are passing through a formative period of their lives. Thus any tendency toward an incorrect posture is likely to become habitual, and the boy may assume a stooped or round shouldered position for the rest of his life. Obviously such a posture has the effect of impairing proper breathing and good health, as well as detracting from proper carriage and appearance.

Thus it is very important that the large number of boys who distribute magazines and papers should not find it necessary to wear any pack carrying contrivance which is conducive to incorrect posture.

It is an object of the present invention to

provide a bag carrying harness which will support the bag upon the wearer's back, and suspend it from the shoulders in such a manner as to evenly distribute the load between the shoulders and the back and have the effect of lightening the load. 65

Another object is to provide a harness which will support the load upon the back in such a manner as to brace the shoulders to promote an erect posture and insure proper breathing. 60

A further object is to provide a harness including a belt member adapted to be inserted in the belt loops of the wearing apparel of the wearer, and thus take the place of the usual belt, means being provided on the belt member for conveniently attaching auxiliary equipment. 65

These and other objects are attained in the present invention by the parts, improvements, and combinations comprising the present invention, which are particularly and distinctly pointed out and set forth in the appended claims, forming part hereof. 70

In general terms the invention comprises a one-piece shoulder bracing and supporting member forming a rear portion of the belt or waistband, and leading therefrom upwardly over the rear of the shoulders, down the front thereof, and around under the arms and across the rear of the shoulders, bag supporting straps secured at one end to the rear shoulder portion of the shoulder bracing member and at the other end to the bag, a belt attached to the rear waistband portion of the one-piece member for supporting wearing apparel and auxiliary equipment, and front belt supporting straps connected at one end to the belt and at the other end to the front shoulder portions of the one-piece shoulder bracing and supporting member. 75
80

90

A preferred embodiment of the improved invention is illustrated in the accompanying drawing, in which 95

Figure 1 is a rear perspective view of the harness and bag in position upon a wearer, portions of the bag being broken away to show the manner of connecting the various members of the harness; 100

Fig. 2, a rear view of the same with the bag detached;

Fig. 3, a front view of a harness and bag detached from the wearer;

Fig. 4, a front view of a harness in position on a wearer, showing the manner of carrying an auxiliary side bag in combination with the regular bag and harness; and

Fig. 5, a detached view of a belt which may be worn with the side bag when the improved harness is not worn.

Similar numerals refer to similar parts throughout the drawing.

A one-piece bag supporting and bracing member indicated generally at 10, has its end inserted through spaced slide rings 11 positioned at the rear of the wearer's waist, and the ends are adjustably connected between the rings as by the buckle 12 to form the rear portion of a waistband or belt adapted to engirdle the wearer's waist. Each end of the one-piece member 10 leads from a ring 11 diagonally upward across the back and over the opposite shoulder, forming the back and shoulder members 14. The members 14 are arranged to cross each other at a point between the shoulder blades as indicated at 15.

From the front of each shoulder the members 14 pass downwardly around the arm pits to form a shoulder bracing loop disposed horizontally across the back of the shoulders as indicated at 16. The shoulder bracing portion 16 is preferably disposed beneath the diagonal back and shoulder members 14 immediately below their crossing point, and may be slidably inserted through a pair of loops 17 each secured to a diagonal member 14, as best shown in Fig. 3, for the purpose of maintaining the bracing member 16 in a substantially horizontal position across the shoulder blades.

The shoulder bracing member 16 may be provided at the middle of the back with a section of elastic material, as indicated at 18, for the purpose of resiliently adjusting the supporting and shoulder bracing member 10 as a whole to various positions of the body, as when the wearer leans forward.

A pair of bag supporting members 20 may be provided, each being secured at one end to the shoulder member 14 at the top rear of the shoulder as at 21, and detachably connected at its other end to the top portion of a bag 22, as by the snap fasteners 23.

The bag 22 is preferably constructed with an oilcloth and fabric outer covering and has a reinforcing inner frame structure of wire and the like as indicated at 22'.

The bag 22 is also detachably connected at its lower portion to the slide rings 11, as by the snap fasteners 24, for the purpose of holding the bag against the wearer's back. Preferably the bag 22 is provided at the side with an opening disposed at the right side of the wearer, and a flap 25 may be provided for closing the opening when desired. Thus arti-

cles carried in the bag may be easily withdrawn by the wearer through the side opening whenever desired.

The flap 25 may be provided with snap fasteners 26, and 26', and is preferably divided into an upper portion 25a and a lower portion 25b, so that when it is desired to carry small articles in the bag, the lower flap portion 25b may be closed to better retain the articles in the bag, and the upper flap portion 25a may be opened to gain access to the interior of the bag.

An adjustable belt 27 is provided for engirdling the wearer's waist, and is secured at the rear to the side rings 11 to form with the portion 13 of the one piece member 10 a complete waist band. The belt 27 is adapted to be inserted in the usual belt loops provided upon the wearing apparel of the wearer, and takes the place of the belt usually worn there-

The belt 27 is preferably buckled at the side of the wearer as by the buckle 28, and a money pouch 29 may be suspended from the front of the belt as by the belt loops 29'.

A pair of tension distributing and belt supporting straps 30 may be provided at the front of the wearer, each being detachably secured at its upper end to one of the shoulder members 14 at the front of the shoulder, as by the buckle 31. The lower end of each strap 30 is provided with a loop 32 through which the belt 27 is slidably inserted. Buckles 33 may be secured to the loops 32 for a purpose to be hereinafter described.

For the purpose of further distributing a very heavy load, leg straps 34 may be provided for engirdling the thighs of the wearer. Each strap 34 is detachably secured at one end to a ring 11, and passed around the thigh, and adjustably secured at the other end to the buckle 33 in a manner illustrated in Fig. 1.

It will be seen that when a load is carried in the bag 22, a pull is exerted rearwardly upon the top of the shoulders, and the shoulder blades are pressed inwardly at the wearer's back by the shoulder bracing member 16, tending to cause the wearer to assume an erect posture. Part of the load is distributed over the back of the wearer due to the fact that the bag is pulled inwardly by the lower belt connections 34 and the tension distributing straps 30 apportion part of the load to the front of the belt.

When the leg straps are worn, part of the load is further distributed to the thighs.

Thus the improved harness has the combined effect of distributing and lightening the load, and of bracing the shoulders in such a manner as to promote erect posture and proper breathing.

The entire harness and bag is preferably made of a strong fabric material faced with oilcloth so as to be very durable and present a neat appearance.

It is sometimes desirable to carry an auxiliary side bag in connection with the improved bag and harness, for the purpose of carrying an extra load, or to serve as a de-

pository for papers which have been taken from the main bag and rolled for throwing.

The manner of wearing the side bag in connection with the improved harness and regular bag is shown in Fig. 4. The side bag 10 35 is supported from the opposite shoulder by means of the diagonal shoulder strap 36 which is adjustably connected to the top of the bag as at 37. Front and rear snap fasteners 38 are provided on the inside top portion 15 of the bag. The front fastener is adapted to be attached to a buckle 33 as shown in Fig. 4, and the rear fastener is adapted to be attached to the adjacent slide ring 11, for the purpose of holding the bag inwardly 20 against the side of the body.

If it is desired to wear the side bag without the improved harness, as by women canvassers, an auxiliary belt 40 illustrated in Fig. 5, may be provided. The belt 40 is 25 adapted to be inserted in the usual belt loops provided on the wearing apparel of the wearer, and is provided with properly spaced rings 41, to which the snap fasteners 38 may be attached.

30 The outside of both the side bag and the regular bag may be utilized for general advertising of any description.

A cap 42, preferably made of the same material as the improved bag and harness, may 35 be worn as shown in Fig. 1 to complete the outfit.

It will be understood that various modifications may be made in the construction and arrangement of the present invention, without departing from the scope of the appended claims.

I claim:

1. A pack carrying harness including a 45 waistband engirdling the front and sides of the wearer's waist, a one-piece strap having its ends adjustably connected together to form a loop portion, means slidably connecting said loop portion to the ends of the waistband, portions of the strap leading from 50 each side of the loop diagonally upward across the back of and over the shoulders of the wearer and thence downward under the arms to form a second loop portion located across the back of the shoulders.

55 2. In combination, a waistband engirdling the front and sides of the wearer's waist and having a ring at each of its ends, and a one-piece shoulder bracing and pack supporting strap having its ends slidably inserted 60 through said rings and adjustably connected together to form the rear waist portion of the waistband, a portion of the strap leading from each ring diagonally upward across the back and forward over the shoulders of 65 the wearer, and thence downward under the

arms to form a loop located across the back of the shoulders, and pack-attaching means at the top rear of each shoulder portion of the strap.

3. A pack carrying harness including a 70 waistband engirdling the front and sides of the wearer's waist, a one-piece strap having its ends adjustably connected together to form a loop portion, means slidably connecting said loop portion to the ends of the waistband, portions of the strap leading from each side of the loop diagonally upward across the back of and over the shoulders of the wearer and thence downward under the arms to form a second loop portion located across the back of the shoulders, and a strap 75 adjustably connected between the front of each shoulder portion of the one-piece strap and the front of the waistband.

4. In combination, a waistband engirdling the front and sides of the wearer's waist and having rings at each of its ends, a one-piece shoulder bracing and pack supporting strap having its ends slidably inserted through said 80 rings and adjustably connected together to form a rear waist portion of the waistband, a portion of the strap leading from each ring diagonally upward across the back and forward over the shoulders of the wearer and thence downward under the arms to form a 85 loop located across the back of the shoulders, pack-attaching means at the top rear of each shoulder portion of the strap, and a strap adjustably connected between the front of each shoulder portion of the one-piece strap and the front of the waistband.

5. In a load carrying harness, a pack, a belt adapted to engirdle the front and sides of the waist of the wearer, a one-piece pack supporting and shoulder bracing member 90 formed in a loop slidably connecting the ends of the belt, portions of said pack supporting and shoulder bracing member being adapted to be disposed over the shoulders and horizontally across the back of the shoulders of the wearer, and means for supporting the pack from the pack supporting and shoulder bracing member at the rear of the shoulders.

6. In a load carrying harness, a pack, a belt adapted to engirdle the front and sides of the waist of the wearer, an adjustable one-piece pack supporting and shoulder bracing member including a loop slidably connecting the ends of the belt and adapted to be disposed over the shoulders and diagonally and horizontally across the back of the shoulders, means for supporting the pack from the pack supporting and shoulder bracing member at the rear of the shoulders, and means for detachably connecting the pack to the belt.

7. A load carrying harness including a belt adapted to engirdle the front and sides of the waist of the wearer, a one-piece adjustable pack supporting member including

a loop slidably connecting the ends of the belt and adapted to pass diagonally upward across the back over the front of the shoulders and horizontally across the rear of the shoulders of the wearer, a pack, means supporting the pack from the top rear portions of the pack supporting member, and means adjustably securing the top front portions of the pack supporting member to the front of the belt.

10 In testimony that I claim the above, I have hereunto subscribed my name.

EVA M. REESE.
